UNITED STATES PATENT OFFICE.

JOHN JOHNSTON, OF ST. LOUIS, MISSOURI.

AUTOMATIC ENVELOP FEEDING, MOISTENING, AND SEALING MACHINE.

No. 821,501.

Specification of Letters Patent.

Patented May 22, 1906.

Application filed May 4, 1903. Renewed December 1, 1905. Serial No. 289,851.

To all whom it may concern:

Be it known that I, JOHN JOHNSTON, a citizen of the United States, residing in the city of St. Louis and State of Missouri, have invented a certain new and useful Improvement in Automatic Envelop Feeding, Moistening, and Sealing Machines, of which the following is a specification.

My invention relates to a new and useful improvement in automatic envelop feeding, moistening, and sealing machines; and the objects of my improvement are, first, to provide a machine that will automatically draw the envelops into the machine or between the feed-rollers of the machine; second, at the same time to moisten or dampen the mucilage or glue on the envelop, and, third, after the mucilage on the envelop has been moistened and the envelop passed through the feed-rollers to seal the envelop by automatically passing it through the sealing-rollers and cast it from the machine. I attain these objects by the mechanism illustrated in the accompanying drawings, in which—

25 Figure 1 is a top plan view of the machine. Fig. 2 is a vertical section of the machine on the line 2 2. The line 2 2 appears in Fig. 1. Fig. 3 is a sectional plan on the line 3 3. The line 3 3 appears in Fig. 2, and Fig. 4 is a side elevation of the machine.

Similar reference-numbers refer to similar parts throughout the several views.

1 is the framework of the machine, which may be of any ordinary construction and may 35 be formed of any suitable material.

The feed-board is in two parts, one removable and the other stationary, and may be made of any suitable material, but preferably of metal. The two parts are joined together, 40 as indicated by the line 2, and when in place are inclined toward the machine, as indicated in Figs. 2 and 4.

3 is the removal part of the feed-board, and to the end nearest the machine is attached or 45 formed integral with it a lip 4, which is to catch under a cross-piece 5, which extends across the machine horizontally and directly in front of the feed-roller 6. 7 is the stationary part of said feed-board, the outward edge 50 of which is fastened to the body of the machine 1, with the inner edge resting on a spring 3, which in turn rests upon the horizontal cross-piece 5, so that when the feed device 9 in the course of its revolutions brings the roller 33 in contact with the inner part of the feed-board 7 the said inner part of the feed-board

is depressed to the position shown by the dotted lines 10, thus preventing the machine from tearing the envelop, at the same time forcing the envelop between the feed-roller 6 60 and feed device 9. The motive power is furnished by a crank 11, which may be turned by hand or other power, and said crank 11 is attached to a main shaft 12, which passes through and serves as an axle for the lower 65 feed-roller 6 and has no vertical movement. 6 is a feed-roller, which with device 9 constitute two feed devices.

14 14 are the moistening-rollers.

15 is the sealing-roller, which seals by contact with the feed-roller 6 and in addition to sealing discharges the envelop from the machine. These rollers 15 6 and device 9 and 14 14 are connected by a train of gears, as shown in the side elevation Fig. 4, the teeth 75 of the wheels being in mesh. The sealing-roller 15 is held in place by the spiral springs 16, so that an envelop with heavy inclosure may pass between the sealing-rollers 15 and 6. The shaft 17, around which the moistening- 80 rollers 14 revolve, has no vertical movement, and the feed device 9 is held apart from the shaft 17 by a spiral spring 51 for the purpose of allowing envelops with thick inclosures to pass between the feed device 9 and feed- 85 roller 6, the teeth of the cog-wheels 50 and 52 being long enough to allow the feed device 9 to rise sufficiently for that purpose and the teeth still remain in mesh.

18 is the water pan or reservoir in which 90 the water is contained for moistening the rollers 14 and from which the water passes through an opening closed by a valve 19 upon a rod 22, which is opened by means of a cam 20 on the end of the shaft 17, which 95 raises an arm 21, attached rigidly to the said rod 22. The valve 19 when loose upon the rod 22 may be kept shut by means of a spring 23. The operation of the said valve is regulated by a screw 24, so that too much water 100 will not pass through into the outer part of said pan under the moistening-rollers. This is accomplished in the following manner: When the screw 24 is set, the horizontal rod 22 raises the valve 19 with every revolution 105 of the cam 20 and allows the water to pass through into the outer part of said pan under the moistening-roller, and when the machine has run a time if too much water passes into the outer part of said pan then if the screw 110 24 is loosened the horizontal rod 22 turns in its socket and does not open valve 19, and the

spring 23 holds the valve 19 shut, and the water does not pass through the opening closed by said valve until the screw 24 is set again. To said shaft 17 are attached on the opposite side from each other and midway between the moistening-rollers 14 two heavy wire projections 27, whose function it is to catch the flaps of the envelopes and straighten them out, so that the moistening-rollers will 10 wet the mucilage or glue on same.

A feature of the feed device 9 is that it consists of a main shaft 28, and to this are fastened two metal circular disks 29, in which is embedded the movable part of the feed-roller 30, which is made of wood or other suitable material and on the outer surface or edge of which is a thin layer of rubber 31. The movable part of said feed device 30 rests on two spiral springs 32, which allow the movable 15 part 30 of the feed device 9 to be depressed when it comes in contact with the feed-board 7, so that it is flush with the outer edges of the circular disks 29. This is for the purpose of preventing the envelopes from being torn 20 and to prevent strain upon the machine. On the ends of the movable part of said feed device 30 are placed two circular resilient disks 33, which by contact lower the feed-board 7 and so allow the envelopes to be drawn, one at 25 a time, into the feed devices without being torn.

As many envelopes with inclosures as the feed-board will hold are placed with the flap up, as indicated by dotted envelop 25. Then 30 the follower 26 is placed behind them to push them toward the machine. The projections 27 straighten up the flaps, if any are down, the moistening-rollers wet the mucilage, and when the rubber of the movable feed device 35 31 strikes the envelop it forces it between the feed-board 7 and the metal disks 29 and also allows the feed-board 7 to be depressed a sufficient time for the first envelop to pass between the feed-rollers, depositing it on the inside of the machine on the incline surface 34, with the flap of the envelop toward the sealing-rollers 6 and 15, as indicated by dotted envelop 35. To the cog-wheel 50, as shown in the side elevation, is attached a cam 36, 40 which every time said cog-wheel revolves raises an arm 37, which is pivotally held by a screw 38 and kept in position by a spring 39, said arm being connected by a link 40 to the eccentrically-mounted bar 41, which is pivot-45 ed in the side frame 1. To the bar 41 are fastened the ejectors 42, which rest back against cross-piece 43. Said ejectors at every revolution of the cam 36 fly forward through the slots 44 and drive the envelop into the sealing-50 rollers 15 and 6, which after sealing the envelop cast it out of the machine down the incline 45. Another feature of the machine is the lever 46, which is pivoted at 47 and fastened to the support for the sealing-roller 15 by bolt 48 and also to cross-piece 49, which

rests on top of the lever 46 and the end of which projects from the side of the machine, as shown. Upon pressing down upon the cross-piece 49 the lever 46 is depressed, thus lowering the sealing-roller 15 to any desired distance, thereby enabling envelopes with heavy inclosures to pass through without straining the machine.

Having thus described the invention, what I claim is—

1. In an envelop feeder, moistener and sealer, the combination of devices for automatically feeding the envelopes into the machine, means for moistening the flaps automatically while the envelop is being fed into the feed devices, means for opening the flaps if shut, sealing-rollers the uppermost thereof being also a part of the feed devices, and means for forcing the envelop automatically into the same substantially as set forth. 75

2. In an envelop feeder, moistener and sealer, the combination of an inclined feed-board, a follower, feed devices, sealing-rollers arranged one above the other, the upper one thereof being the lower part of the feed devices, moistening-rollers, a water-reservoir, and means for dampening said moistening-rollers from the water-reservoir, devices for straightening out the flaps if any are turned down and means for depressing said feed-board adjacent to the feed devices to prevent the envelopes from being torn and to prevent strain upon the machine, all substantially as set forth. 80

3. In an envelop feeder, moistener and sealer the combination of a train of gears for furnishing the power from one main shaft or rod, feed devices arranged one above the other, the upper one being movable vertically when in use to prevent undue strain on the machine, sealing-rollers, the upper one thereof being the lower part of the feed devices, vertically-movable bearings for the lower sealing-roller so that it may yield when envelopes pass through, and means for forcing the envelopes between the sealing-rollers, all substantially as set forth. 90

4. In an envelop feeder, moistener and sealer the combination of one feed-roller 6 and feed device 9 for carrying the envelop into the machine, an incline therein to receive the envelop and reverse the motion thereof, sealing devices consisting of the feed-roller 6 in conjunction with a roller 15 for sealing the envelop and ejecting it from the machine, means for automatically moistening the flaps of the envelopes before they are drawn into the feed devices, means for automatically straightening the flaps, means for carrying the envelop into the machine without tearing it and without strain on the machine, and means for forcing the envelopes into the sealing-rollers, all substantially as set forth. 105

5. In an envelop feeder, moistener and 110

sealer, the combination of a main shaft and a train of gears for furnishing the power, one feed-roller 6 and feed device 9 driven by said shaft and gears for carrying the envelops into the machine, an incline on the inside of the machine for reversing the motion of the envelop, a movable roller arranged to operate in connection with the feed-roller 6 as sealing devices, means for moistening the flaps of the envelops before they are drawn into the feed devices, means for dampening

the moistening-rollers, means for straightening the flaps, and means for forcing the envelops between the sealing-rollers, all substantially as set forth.
